UNITED STATES PATENT OFFICE.

THOMAS HOPKINS, OF NEWPORT, KENTUCKY.

SACK-FASTENER.

Specification of Letters Patent No. 29,695, dated August 21, 1860.

To all whom it may concern:

Be it known that I, THOMAS HOPKINS, of Newport, Campbell county, Kentucky, have invented a new and useful Sack-Fastener; and I do hereby declare the following to be a full, clear, and exact description thereof, reference being had to the accompanying drawings, making part of this specification.

10 My invention relates to devices for securely tying or closing up the mouths of sacks, bags, &c., and consists of two pins or buttons and a connecting link constructed and combined, as hereinafter explained, so 15 as to be permanently secured in position and afford means of attaching the string to the bag and of securing its free end.

In the accompanying drawings Figure 1 exhibits the construction of the fastener before permanent attachment to the sack. Fig. 2 represents the instrument for permanently securing the fastener to the sack. Fig. 3 is a section of the fastener before attachment. Fig. 4 is a section of the same 25 after attachment. Fig. 5 shows the mode of securing the tying string to the fastener. Fig. 6 shows the mouth of bag and fastener when string is secured.

A and A' are two buttons formed of ob- 30 long or cylindrical pieces of wood contracted toward each end and at their middle. B is a ring or yoke which at first is of the

oblong form seen in Figs. 1 and 3. A hole being punched in the sack the ring B is pro- 35 truded half way through the side of the sack and a button inserted into each end. The center part of the ring is then compressed as seen in Figs. 4, 5, and 6. For this purpose I employ a pair of pincers such as represented at Fig. 2. One end of a string C being now 40 secured to the ring B—the fastening is ready for use.

In use the mouth of the sack is gathered in the usual way and the free end of the string being wound once or more around 45 the sack is then pulled forcibly between the button A and the sack side and wound several times around the ring between the buttons and the sack is fastened, the large parts of the buttons effectually preventing the es- 50 cape of the end.

I claim as new and of my invention herein—

A sack fastener consisting of two pins or buttons A and A' and a connecting link B, 55 constructed and combined in the manner and for the purposes set forth.

In testimony of which invention, I hereunto set my hand.

THOMAS HOPKINS.
